J. M. FULLER

PERFORATED SHEET

Filed May 5, 1919

Patented June 2, 1925.

1,540,325

UNITED STATES PATENT OFFICE.

JUDSON M. FULLER, OF OAK PARK, ILLINOIS, ASSIGNOR TO THE HARRINGTON AND KING PERFORATING CO., OF CHICAGO, ILLINOIS, A CORPORATION OF ILLINOIS.

PERFORATED SHEET.

Application filed May 5, 1919. Serial No. 294,842.

To all whom it may concern:

Be it known that I, JUDSON M. FULLER, a citizen of the United States, residing at Oak Park, in the county of Cook and the 5 State of Illinois, have invented certain new and useful Improvements in Perforated Sheets, of which the following is a specification, reference being had to the accompanying drawings, forming a part thereof.

10 This invention relates to a supporting sheet adapted for various purposes and especially for insertion between a filter cloth, a fine mesh metal screen or similar flexible and pervious element, and a rigid frame or 15 backing wall, for the purpose of spacing the filter sheet or screen from such backing,—the supporting sheet being designed to present the minimum of obstruction to the flow of the filtrate or liquor, both through the 20 screen and in the space formed between such screen and the rigid backing. It consists of the features of construction hereinafter described and shown in the drawings as indicated by the claims.

25 In the drawings:

Figure 1 is a bottom plan view of a fragment of a sheet of perforated material embodying this invention.

Figure 2 is a sectional view of the sheet 30 shown in Figure 1, drawn to a slightly larger scale and taken as indicated at line 2—2 on Figure 1.

Figure 3 is a bottom plan view of a perforated sheet of slightly different form but 35 also embodying the invention.

Figure 4 is a section taken as indicated at line 4—4 on Figure 3.

40 Figures 5 to 14 inclusive show various modified arrangements of rectangular perforations with rectangular lugs extending from one or more edges thereof, but all included within the scope of this invention. In each case the view is a bottom plan of a fragment of a sheet.

45 Figures 15 to 18 inclusive are bottom plan views of further modifications in which the polygonal perforations are shown as triangular with supporting lugs extending from either one or two sides or edges of each aperture.

50 Figure 19 is a bottom plan view of a fragment of a sheet illustrating one more modification in which the apertures are hexagonal with supporting lugs extending from several edges of each.

There are many situations in manufacturing apparatus and processes, particularly those involving the operations of straining, filtering or screening, in which it is desirable to support a screen or filter cloth of 60 relatively fine mesh against the fairly heavy pressure involved in the operation. Usually a screen or cloth, whether of perforated metal, woven wire, or vegetable fabric, if it is of sufficiently fine mesh to perform the 65 work required, it is necessarily rather thin and quite flexible, but not particularly strong. The operations in which such pervious or perforate sheets are employed, however, frequently involve the use of heavy 70 pressure such that if a filtering membrane were merely stretched over a marginal supporting frame, it would be wholly inadequate to withstand such pressure and would be promptly ruptured. Under such circumstances the filter sheet or screen is therefore 75 usually supported by a fairly rigid backing wall extending over the entire exposed area of the pervious sheet but spaced from it in a substantially parallel plane to permit of 80 drainage of the filtrate or liquor passing through the sheet under the pressure applied, and this spaced relation is maintained by either providing the backing wall with a corrugated surface coming in contact with 85 the pervious sheet only at certain lines or points in its area, or providing a member formed to serve in the same way as a spacing element supported on the rigid wall and contacting with the pervious sheet at regularly spaced points, leaving relatively small, though many, unsupported areas which are unobstructed for the passage of the filtrate through them. It is the purpose of the 90 present invention to provide such a supporting element to be interposed in apparatus presenting the above-indicated requirements.

95 The specimen fragment of a perforated sheet as shown in Figure 1 may be understood as of sheet metal of a moderate gauge 100 or thickness having two series of apertures, 1, and 2, arranged in alternating rows,—the apertures, 2, being punched cleanly through by complete removal of the material representing their respective areas, while the 105 apertures, 1, are formed by cutting this material free from the remainder of the sheet at two opposite and parallel edges, and bending it to extend as a pair of transverse lugs or feet, 3, from the other pair 110

of opposite and parallel edges which complete the outline of each aperture, 1, as shown. If the lugs thus formed would be longer than desired, the first operation in forming the apertures, 1, would be to punch out a middle section of the area, thus, in effect, cutting off the extreme end portion of each lug, 3, before bending out the latter.

10 In this view, the apertures, 2, are shown arranged in staggered relation to the apertures, 1, of the alternate rows, and the result is indicated in section in Figure 2, which shows how the bending of the lugs, 3, tends to arch up the material at 4, between the adjacent apertures, 2, and between the lugs of adjacent rows of the type of apertures, 1. This makes a corrugated surface at the side of the sheet A, opposite that from which the lugs, 3, extend, so that, if, as indicated in Figure 2, this sheet, A, is interposed between a rigid backing wall, X, and a finely perforated, thin screen, Y, or other pervious sheet, said sheet, A, will stand in actual contact with the sheet, Y, at the minimum area, because of the arched formation of the parts, 4, which thus stand above the remainder of the uncut area of sheet, A, and tend to support the membrane or sheet, Y, slightly spaced away even from this remaining area of the interposed element, A. Thus a large percentage of the total area of the pervious member, Y, is left quite unobstructed for the passage of the filtrate through its perforations or meshes. The drawing is not intended to indicate any particular direction of flow for the filtrate over the surface of the backing wall, X, but if this part stands vertical or inclined it will be evident that such flow will be least obstructed if the sheet, A, is arranged with its feet or lugs, 3, standing edge-wise in the current of the flow,—that is, so that Figure 2 would properly represent a section taken looking in the direction of such flow or movement.

15 A modified design of sheet is shown at B, in Figures 3 and 4, in which an aperture is indicated at 1, and is of the type formed by bending out at one of its edges, a lug, 3, for contact with the supporting surface of wall X, but for the better distribution of these supporting lugs over the under surface of the pervious sheet, shown in Figure 4 as a woven wire screen, Z, these lugs, 3, are bent alternately from the opposite sides of adjacent apertures, 1, of each row.

20 Figure 5 shows a fragment, C, in which the lugs, 3, are all arranged at the same, or corresponding edges of their respective apertures, 1. In Figure 6, the fragment, D, presents a similar arrangement, except that the apertures, 1, themselves are placed in staggered relation. In Figure 7, the frag-

ment, E, has staggered apertures, 1, in which the lugs, 3, extend all from the same or corresponding sides of the openings, as distinguished from the top or bottom, so that the bent lugs, 3, are themselves in 70 staggered rows if considered in their relation edge-wise to each other.

25 The openings shown in the first seven figures of the drawing are approximately square, but to indicate that this is not an 75 essential feature, the specimens, F, G, H, I, J, K and L, shown in Figures 8 to 14, inclusive, are made with oblong apertures, all designated by the character, 1, and each opening formed with one or more lugs, 3, 80 extending from an edge or certain edges, for supporting the screen or filter cloth, as already described. The specimens, M, N, O, and P, shown in Figures 15 to 18, inclusive, 85 present triangular apertures variously arranged in respect to each other, and some with one and others with two lugs, 3, bent out from their edges. Specimen, Q, of Figure 19, shows an even more elaborate design comprising polygonal apertures of hexagonal form, each having lugs, 3, bent out from several of its edges. This multiplication of examples is merely to emphasize the fact that polygonal apertures of three, 90 four, six, or any other number of sides may be employed without departure from the spirit and scope of this invention, and that it is not of particular importance whether each of such apertures is made with only a single lug or foot, 3, or with several such 95 supporting members, bent off from its edges; nor is it important that every one of the openings in the interposed sheet be formed with such lugs; and many additional modifications of structure and arrangement may 100 still be made within the spirit of the invention and of the appended claims defining the same.

30 I claim:

1. A support for a filter screen or the like 110 comprising a reticulated sheet having polygonal apertures with the material cut from said apertures bent to extend perpendicularly from the plane of the sheet at the side opposite its screen supporting surface and from one or more edges of said apertures, 115 but not from all edges of any, thus forming lugs for spacing the sheet from a supporting surface; the outer ends of such lugs being cut on straight lines lying in a common plane 120 parallel to that of the sheet.

2. A sheet, having polygonal apertures arranged in staggered rows with the material cut from said apertures bent to extend from each of two opposite sides of the apertures of each alternate row whereby the material between the apertures of intervening rows is arched up between adjacent lugs of the rows adjacent so that the surface 125 of the sheet is corrugated.

3. In a sheet as defined in claim 1, the said apertures being rectangular, and the lugs extending therefrom being also rectangular.
- 5 4. A sheet having rectangular apertures arranged in staggered rows with rectangular lugs bent to extend from each of two opposite sides of each aperture of each alternate row, whereby the material between the

apertures of intervening rows is arched up 10 between adjacent lugs of the rows adjacent, and thus the surface of the sheet is corrugated.

In testimony whereof, I have hereunto set my hand at Chicago, Illinois, this 2nd day 15 of May, 1919.

JUDSON M. FULLER.
